DESIGN FOR A CASING FOR A BILLIARD
SCORING DEVICE OR THE LIKE

Richard K. Morse, Fruitport, Mich., assignor to The Brunswick-Balke-Collender Company, Chicago, Ill., a corporation of Delaware

Application March 5, 1948, Serial No. 144,913

Term of patent 14 years

(Cl. D34—3)

To all whom it may concern:

Be it known that I, Richard K. Morse, a citizen of the United States, residing at Fruitport, in the county of Muskegon, State of Michigan, have invented a new, original, and ornamental Design for a Casing for a Billiard Scoring Device or the like, of which the following is a specification, reference being had to the accompanying drawings, forming a part thereof.

Fig. 1 is a top plan view of a casing for a billiard scoring device or the like, showing my new design;

Fig. 2 is a front elevational view thereof;

Fig. 3 is an end view, looking at the right-hand end of Fig. 2;

Fig. 4 is a fragmentary section along the line 4—4 of Fig. 2.

The dominant features of the invention are shown in full lines.

I claim:

The ornamental design for a casing for a billiard scoring device or the like, as shown and described.

RICHARD K. MORSE.
